UNITED STATES PATENT OFFICE

CHARLES BOSICK, OF JEFFERSON COUNTY, COLORADO

VEHICLE LIFT

Application filed April 10, 1928. Serial No. 268,868.

An object of this invention is to provide an improved lift or elevator for vehicles such as automobiles, trucks and the like, whereby said vehicles may be lifted to suitable elevations for repair, greasing and oiling or other maintenance operations.

A further object of the invention is to provide an improved vehicle lift or elevator which is operated by mechanical rather than 10 hydraulic means, thereby dispensing with the use of expensive pumps, compressors and similar machines necessary to the operation of hydraulic lifts.

A further object of the invention is to provide an improved lift or elevator for vehicles adapted to engage and lift vehicles in such manner as to leave the wheels thereof free for rotation and repair.

A further object of the invention is to provide an improved vehicle lift or elevator adapted to be driven and operated by any convenient form of hand or mechanical power.

A further object of the invention is to be 25 found in the provision of means whereby an improved vehicle lift or elevator may be automatically supported and maintained at any desired elevation.

A further object of the invention is to be 30 found in the provision of an improved vehicle lift or elevator that is positive and efficient in operation, simple and inexpensive of manufacture and installation, economical to maintain and susceptible of installation in 35 any suitable location.

My invention consists in the construction, arrangement and combination of elements hereinafter set forth, pointed out in my claims and illustrated by the accompanying 40 drawing, in which—

Figure 1 is a side elevation of the improved lift or elevator as installed for practical use and in elevated position, dotted lines indicating the retracted position thereof. Figure 45 2 is a plan view of the showing of Figure 1.

Figure 3 is a vertical section on the indicated line 3—3 of Figure 2. Figure 4 is a horizontal section on the indicated line 4—4 of Figure 1, certain parts being broken away to conserve space. Figure 5 is a plan of the 50 pit installation for the improved lift or elevator, all moving or operating parts being omitted; dotted lines indicating alternative positions of one of the elements.

In the construction of my improvement as 55 shown, a platform is composed of rails 10, 11 secured in parallel, spaced relation to a plate 12 positioned transversely of and beneath mid-portions of said rails, the spacing of said rails and the width of said plate 60 being less than the standard gauge of vehicles, so that a vehicle may be driven or positioned in straddling relation above said platform when the latter is in lowered position. Spacing bars, 13, may be fixed between the rails 10 and 11 to preserve said rails in proper relative alignment and an apertured plate, 14, is positioned transversely 65 of said rails adjacent one end thereof and fixed thereto, said plate 14 serving to further brace and strengthen the platform assembly and having an aperture of such size and shape as to receive and accommodate the differential housing of a motor vehicle when 70 and as the platform is elevated into lifting 75 position. A relatively long screw 15, having external threads of low pitch, is rigidly secured to and extends downwardly from and at right angles to the plane of the plate 12 and centrally of said plate, said screw being 80 slidably received for free axial reciprocation in a tube or housing 16 vertically disposed beneath, centrally of and opening into a pit 17. Tubes or cylinders 18, 19, similar 85 to the tube 16, are vertically disposed in parallel relation with and spaced on opposite sides from said tube 16 with their upper ends opening into the pit 17 and cylindrical guides 20 and 21 are slidably mounted for 90 axial reciprocation in the cylinders 18 and 95

19, respectively, and are rigidly secured at their upper ends to the plate 12 of the platform. It is of course obvious that the guides 20 and 21 and the slide bearings 18 and 19 may have any desired shape in cross section so long as said guides fit snugly and are free to slide longitudinally within said bearings. The guides 20 and 21 are preferably relatively longer than the screw 17 so that said guides will still have a portion of their lengths engaged in the slide bearings when the lower end of the screw 13 has been raised above the upper end of the tube 16. As shown in Figure 3, the upper and lower ends 15 of the tubes 16, 18 and 19 may be secured in proper relative position by surrounding them with concrete or cement. A bevel gear 22 having an axial bore and internal threads corresponding to the threads of the screw 15 within said bore, is mounted in threaded engagement on and about the screw 15 in position to rotate between the guides 20 and 21 adjacent the floor of the pit 17, and a plate 23 is mounted on the floor of said pit beneath said gear 22, said plate 23 supporting anti-friction devices such as a ball bearing 24 to receive the thrust from the said bevel gear 22. Thus is provision made for raising and lowering the platform above described, since rotation of the gear 22 in one direction will operate to raise the screw 15, plate 12, guides 20 and 21 and rails 10 and 11, while reverse rotation of said gear will permit the platform assembly carried by the screw 15 to be lowered, the low pitch of the threads on said screw serving to hold the platform in any desired position when the gear 22 is held stationary or not rotated. The plate 23 is extended radially of the tube 16 and supports journals 25 and 26 in spaced relation beyond and extending above said gear 22, and a shaft 27 having a bevel pinion 28 on one end in meshing relation with the gear 22, is mounted for rotation in the journals 25 and 26 and extends radially of the gear 22 through a trough or channel 29 opening through one side of the pit 17, the remote end of said shaft being supported by a journal bearing 30 in any convenient location and carrying a means of receiving power, such as a belt wheel 31, hand crank, crank throw, sprocket wheel or the like. As indicated by dotted lines in Figure 5, the plate 23 may be set at the time of installation at any angle to the pit 17 to afford convenient passage for the shaft 27.

In the practical operation of my improvement, any suitable power connections having been made between the remote end of the shaft 27 and a source of power, application of power to said shaft will rotate the pinion 28 and drive the gear 22, rotation of said latter gear acting on the screw 15 to raise said screw and the platform carried thereby, reverse driving of the pinion 28 serving to

lower the screw 15 and platform. The spacing of the rails 10 and 11 being less than the standard vehicle gauge, a vehicle may be moved into straddling relation over said rails the differential housing of said vehicle positioned above the apertured plate 14 and the driving mechanism of the lift actuated to raise said rails, whereupon the rails in their upward travel will engage beneath the axles of said vehicle and raise said vehicle. It is readily to be seen that the engagement of the rails 10 and 11 with the axles or fixed portions of the vehicle leaves the wheels thereof free to rotate and makes adjustments and repairs of said wheels a simple and expeditious task without the necessity of further jacking or elevating said wheels. Likewise, the skeleton form of the supporting platform permits free access to various parts of the vehicle, facilitating and expediting any work to be done thereon.

Since many changes or modifications of form and construction may be had without departing from the spirit of my invention, I wish to be understood as being limited by the scope of the appended claims rather than any description or illustrative showing of the improvement.

I claim as my invention—

1. A vehicle lift comprising a skeleton platform, an externally-threaded screw and guides in spaced, parallel relation depending at right angles from said platform, spaced, vertically-disposed slide bearings adapted to receive said screw and guides, a transverse plate on the upper end of the slide bearing for said screw, an internally-threaded gear rotatable on and in threaded engagement with said screw above said plate, an anti-friction device between said gear and plate, spaced journal bearings carried by said plate, a shaft mounted for rotation in said journal bearings and extending radially of said gear, a pinion on one end of said shaft in meshing engagement with said gear and power receiving means on the other end of said shaft.

2. The combination with a pit having a laterally-extending passage of vertically-disposed slide bearings in spaced, parallel relation beneath and opening into said pit, one of said slide bearings being centrally disposed relative to said pit, a skeleton platform above and overlying said pit, an externally-threaded screw fixed to and depending centrally at right angles from said platform and in sliding engagement with said central slide bearing, guides fixed to and depending in spaced, parallel relation with said screw from said platform and in sliding engagement with said other slide bearings, a plate in said pit surrounding and extending radially from the upper end of said central slide bearing, an internally-threaded gear rotatable on and in threaded engagement with said screw above said plate, an anti-friction device be-

tween said plate and gear, spaced journal bearings carried by said plate, a shaft mounted for rotation in said journal bearings and extending radially of said gear, a pinion on 5 one end of said shaft in meshing relation with said gear, said shaft extending along said passage from said pit and having power receiving means on its remote end.

Signed at Denver, in the county of Denver 10 and State of Colorado, this 20th day of March, 1928.

CHARLES BOSICK.
